United States Patent Office

Des. 205,938
Patented Oct. 11, 1966

205,938

AUDIO SPEAKER CABINET

Charles Jimenz, 1880 Gladwick St., Compton, Calif.

Filed Oct. 23, 1965, Ser. No. 87,874

Term of patent 7 years

(Cl. D14—6)

FIGURE 1 is a front perspective view of the audio speaker cabinet, showing my new design;

FIGURE 2 is a rear perspective view thereof;

FIGURE 3 is a top plan view thereof;

FIGURE 4 is a bottom plan view thereof;

FIGURE 5 is an end elevation thereof, looking from the right end of FIGURE 2; and,

FIGURE 6 is an end elevation thereof taken from the left end of FIGURE 2.

The portions shown in broken lines in FIGURE 1 are included for illustrative purposes only.

I claim:

The ornamental design for an audio speaker cabinet, substantially as shown and described.
